ATTYS.

UNITED STATES PATENT OFFICE.

EDWARD D. WOODS, OF GRANVILLE, NEW YORK, ASSIGNOR TO THE WOODS SPECIALTY COMPANY, OF NEW YORK.

CORN-KNIFE.

SPECIFICATION forming part of Letters Patent No. 628,594, dated July 11, 1899.

Application filed May 26, 1898. Serial No. 681,778. (No model.)

To all whom it may concern:

Be it known that I, EDWARD D. WOODS, a citizen of the United States, and a resident of Granville, Washington county, State of New York, have invented a new and useful Improvement in Corn-Knives, of which the following is a specification.

My invention relates to improvements in corn knives or cutters. Its object is to provide a strong, substantial, and cheaply-made corn-knife whose blade can be readily closed when not in use and quickly opened when needed. It consists of the improved devices herein shown and described.

Referring now to the drawings which form a part of this specification, and in which like reference-letters refer to like parts in the various views, Figure 1 is a side elevation of a corn-knife embodying my invention, showing the blade folded. The dotted lines in this figure show the position the blade assumes when it is extended. Fig. 2 is a top view with the blade extended. Fig. 3 is a vertical section of the upper end of the handle at right angles to the blade, the section being taken on the line 4 4 of Fig. 4, looking in the direction of the arrow. Fig. 4 is a vertical elevation at right angles to Fig. 3—that is, on line 3 3 of Fig. 3—looking in the direction of the arrow.

The handle A is slotted at its upper end to receive the tang of the blade B. A rivet *a* passes through handle and tang and through the split ferrule *b*, that encircles the handle at this point. The rivet *a* pivots the blade in the slot, and about it the blade turns. Another rivet *c*, which secures the ferrule *d* to the end of the handle, passes through the slot in the handle, and thus serves to strengthen the handle. It serves also to assist the rivet *a* to hold the blade in the handle by taking a part of the strain when the blade is in use. It serves also as a stop to keep the blade from opening too far. Secured by the rivets to the side of the handle is the spring-catch C, whose upper and free end lies across the end of the handle at right angles to the blade in a slot cut for it in the ferrule *d*. This ferrule has

also a slot in its side corresponding with the slot in the handle.

The blade B is of any usual or desired form; but its tang has on its rear edge a notch *e* and on its upper edge a notch *f*. This upper edge curves downward from the notch *f* to the rear edge.

The operation is as follows: Taking the knife with the blade in the position shown in Fig. 1, the blade is lifted with the fingers till it approaches the position shown in dotted lines, turning about the pivot *a*. As it approaches this position the spring C rides upon the curved upper edge of the tang, and when it reaches it the spring snaps into the notch *f* and holds the blade securely in position. At this time the rivet *c* fits into the notch *e*. Thus the blade is as firmly held in the handle and is as well able to resist the strains incident to use as if both rivets passed through holes in the blade, as is usually done. By raising the spring-catch C with the fingers the notch *f* is released, and the blade can be closed.

My improved devices provide a corn-knife which when not in use can be easily and compactly folded together, thus rendering its transportation and storage easier, cheaper, and safer, which can instantly and readily be put into condition for use, and which is just as strong and as capable of withstanding the strains of ordinary use as are corn-knives having their blades securely and permanently fastened in an open position to the handles.

What I claim as new, and desire to secure by Letters Patent, is—

The combination of a slotted handle, a blade pivoted in the slot, a rivet securing a ferrule to the handle and adapted to engage a notch in the blade, and a catch to hold the blade open, substantially as described.

In testimony whereof I have signed my name to this specification in the presence of two subscribing witnesses.

EDWARD D. WOODS.
